UNITED STATES PATENT OFFICE.

JOSEPH I. CONNELLY, OF CHICAGO, ILLINOIS.

BURGLAR ALARM.

Application filed May 13, 1922. Serial No. 560,627.

To all whom it may concern:

Be it known that I, JOSEPH I. CONNELLY, a citizen of the United States of America, and a resident of Chicago, county of Cook, 5 and State of Illinois, have invented a new and useful Improvement in Burglar Alarms, of which the following is a specification.

This invention relates to burglar alarm devices for attachment to closures such as 10 doors and windows.

The main objects of this invention are to provide a burglar alarm device serving both as a lock for securing a door or window against opening and also as an alarm 15 for giving audible signal when an opening is attempted while the lock is set; to provide a device of the above character including improved means for shifting the locking element into and out of locking position; and 20 to provide a burglar alarm device which is simple and effective and which may be readily attached to the door or window by means of a few screws.

An illustrative embodiment of this invention 25 is shown in the accompanying drawings wherein—

Figure 1 is a side elevation of a device embodying this invention adapted for use on a door, the bell of the alarm being removed for the sake of clearness, and the door being shown in a fragmentary elevation.

Fig. 2 is a top plan of the device shown 30 in Figure 1, the bell and door being shown in section.

Fig. 3 is a top plan of a device embodying this invention and adapted for use on a window, a part of the latter being shown in section.

Fig. 4 is a side elevation of the device 35 shown in Figure 3 and showing the window in section.

In the form shown, the invention is embodied in a device including a support for attachment to one part of the closure and a locking bolt which is shiftable into and out of coacting relation with a keeper formed on the other part of the closure. Mounted 40 on the locking bolt is an alarm including the usual spring motor and detent. A control element for normally holding the spring motor inactive is also mounted on the locking bolt and is arranged so as to be actuated for releasing the escapement detent when the control element is forced against

the keeper by pressure applied transversely to the locking bolt, as when a forced entry is attempted while the closure is locked by the locking bolt.

Referring to Figures 1 and 2 of the drawings, the locking and alarm device is shown applied to a doorway including a hinged door 1, and a door jam 2 having the usual keeper 3 for receiving the locking bolt.

The door attachment shown in Figures 1 and 2 comprises a supporting plate 4 having means for attachment to one of the parts of the closure and having slidably mounted thereon a locking bolt 5, which carries an audible signal device 6.

In the form shown, the supporting plate 4 is secured to the hinged door 1 by screws 7. The locking bolt 5 is provided with a longitudinally extending centrally located slot 8 slidably engaging a pair of retaining screws 9 mounted on the supporting plate 4. Mounted on one end of the locking bolt 5, is a knob 10, whereby the bolt is manually shifted into and out of engagement with the keeper.

The signal device 6 comprises a supporting frame 11 fixed on the locking bolt 5 for supporting thereon the usual form of spring motor 12, including a bell 13 mounted on a central post 14, and an escapement 15 which carries a hammer 16. The detent 15 is normally locked by a control element 17 for holding the spring motor inactive.

The control element shown in Figures 1 and 2 comprises a dog 18 arranged in longitudinally extending slot 19 formed in the locking bolt 5. The dog 18 is pivotally secured to the locking bolt 5 by a pin 20, and is provided at its inner end with a lug 21 which coacts with a shoulder in the form of a projecting part 22 formed on the detent 15 for normally locking the latter against operation. The lock 21 is normally held in engagement with the shoulder 22 by a spring 23 which bears against the inner end of the dog 18. The outer end of the dog 18 forms a tripper which projects beyond the outer face of the locking bolt so as to coact with and be actuated by the keeper 3 when a forced entry is attempted while the closure is locked.

Referring to Figures 3 and 4, the device is shown applied to a window, including upper and lower sashes 24 and 25 respec-

tively, and frame 26. In the form shown, the window attachment comprises a supporting plate 27, on which is mounted a locking bolt 28, which carries an alarm device similar to that shown in Figures 1 and 2. In the form shown, the supporting plate 27 is fastened to the upper cross piece 29 of the lower sash 25.

The control element of the window attachment comprises a dog 30, seated in a slot 31 formed in the locking bolt 28, and pivotally secured to the locking bolt by a pin 32. The inner edge of the dog 30 co-acts with a member 33 carried by the escapement detent, not shown, for normally locking the detent against operation. The outer end of the dog 30 forms a tripper which is arranged at the inner end of the locking bolt 28, so as to be adapted to coact with a keeper 34 in the form of a bar carried by the upper sash 24 and slotted to provide shoulders 35. The outer end of the locking bolt 28 extends through a latch member 36 and is provided with a pivoted arm 37 for engagement with lugs 38 formed on the latch member for securing the locking bar in its operative position, as shown in Figures 3 and 4. To shift the locking bar 28 out of operative position, the pivoted arm 37 is raised to clear the lugs 38, so as to permit the locking bar to be shifted around its pivot.

In operation, to lock the closure, the locking bolt is shifted into coacting relation with the keeper, as shown in Figures 2 and 4. In the event that a forced opening is attempted while the locking bolt occupies its closed position, the tripper arm or dog is forced against the keeper which releases the inner edge of the dog from the escapement detent, permitting the spring motor to actuate the bell hammer.

Although but one specific embodiment of this invention has been herein shown and described, it will be understood that numerous details of the construction shown may be altered or omitted without departing from the spirit of this invention as defined by the following claims.

50 I claim:

1. The combination with a keeper of a locking and alarm device comprising a support, a locking bolt arranged on said support and movable relative thereto so as to be shiftable into and out of coacting relation with the keeper, an alarm including a spring motor, a detent for normally holding said motor inactive, a control element arranged to release said detent, said control element being mounted on said locking bolt in position to be adapted to contact with the keeper and be actuated thereby when said control element is forced against the keeper by pressure applied transversely to the locking bolt.

2. The combination with a keeper of a locking and alarm device comprising a support, a locking bolt arranged on said support and movable relative thereto so as to be shiftable into and out of coacting relation with the keeper, an alarm including a spring motor, a detent for normally holding said motor inactive, a dog pivotally mounted on said locking bolt and arranged for releasing said detent, said dog being located in position to be actuated by the keeper when said dog is forced against the keeper by pressure applied transversely to the locking bolt.

3. The combination with a keeper of a locking and alarm device comprising a support, a locking bolt arranged on said support and movable relative thereto so as to be shiftable into and out of coacting relation with the keeper, an alarm including a spring motor, a detent for normally holding said motor inactive, a dog pivotally mounted on said locking bolt and arranged to coact with said detent, and a spring normally holding said dog in position for locking said detent against operation, said dog being located in position to be actuated by the keeper when said dog is forced against the keeper by pressure applied transversely to the locking bolt.

4. The combination with a keeper of a locking and alarm device comprising a support, a locking bolt arranged on said support and movable relative thereto so as to be shiftable into and out of coacting relation with the keeper, an alarm including a spring motor and escapement detent, a hammer actuated by said detent, a shoulder formed on said detent, and a dog pivotally mounted on said locking bolt, one end of said dog being arranged to coact with said shoulder for normally locking said detent against operation, the other end of said dog being arranged to form a tripper movable transversely to said locking bolt.

5. The combination with a keeper of a locking and alarm device comprising a support, a locking bolt arranged on said support and movable relative thereto so as to be shiftable into and out of coacting relation with the keeper, an alarm mounted on said locking bolt and including a spring motor, a detent for normally holding said motor inactive, and a dog pivotally mounted on said locking bolt and arranged for releasing said detent, said dog being located in position to be actuated by the keeper when said dog is forced against the keeper by pressure applied transversely to the locking bolt.

6. The combination with a keeper of a locking and alarm device comprising a support, a locking bolt arranged on said support and movable relative thereto so as to be shiftable into and out of coacting rela-

tion with the keeper, an alarm including a spring motor mounted on said locking bolt, an escapement detent for normally holding said motor inactive, a hammer mounted on said detent, and a dog pivotally mounted on said locking bolt and normally held in position for locking said detent against op-

eration, said dog being located in position to be actuated by the keeper when said dog is forced against the keeper by pressure applied transversely to the locking bolt. 10

Signed at Chicago this 4th day of May 1922.

JOSEPH I. CONNELLY.
